UNITED STATES PATENT OFFICE

ALLEN B. NORTON, OF CLEVELAND, OHIO, ASSIGNOR TO ALUMINUM COMPANY OF AMERICA, A CORPORATION OF PENNSYLVANIA

SEMI-PERMANENT MOLD AND METHOD OF MAKING THE SAME

Application filed August 21, 1929. Serial No. 387,310.

This invention relates to the casting of metal in molds having sand cores. More particularly it relates to a method of and an apparatus for making and utilizing green sand cores.

It has been customary to cast metal around a core made of sand and it is customary to provide the sand core with a print which functions to support and position the core within the mold. In semi-permanent mold work it has previously been customary to fashion the core out of baked sand in order to bind the sand sufficiently to make it retain its shape during handling or to ram sand about an arbor and use the core without baking. Heretofore the baked sand cores with suitable core prints have been made in a core box and subsequently transferred to a bake oven on supporting metal plates, which metal plates are removed after baking and before the cores are inserted in the molds for casting purposes. The step of baking sand cores is costly and time-consuming. The green sand arbor type cores were not adaptable to all castings because of the difficulty of properly ramming the sand about the arbor and later removing the arbor from the casting.

It is therefore an object of this invention to provide a green sand core assembly which can be utilized without a core print or arbor in making castings where baked sand cores have hitherto been employed. It is a further object to provide an improved method of making a green sand core assembly. Another object is to provide an improved mold and green sand core assembly.

Other objects will be apparent from the specification and from the accompanying drawings in which latter.

Fig. 1 is a top plan view of a mold containing sand core assembly embodying my invention.

Fig. 2 is a vertical sectional view taken along the line 2-2 of Fig. 1.

Fig. 3 is a transverse sectional view of a core body showing one step in forming a green sand core according to my invention.

Fig. 4 is a view similar to Fig. 3 but showing a subsequent step in forming a green sand core, and

Fig. 5 is a transverse sectional view through the completed green sand core assembly.

Referring particularly to Figs. 3, 4 and 5 of the drawings, in its preferred embodiment, the green sand core assembly comprises the core 1 which is carried on the supporting plate 2 on which it is centered by means of engagement with spaced ribs 3 which project outwardly from the plate 2, and extend into the same. The plate 2 carries the positioning flanges 4 and 5 which function to position and support the same in a core box and also in a mold to be later described. When the mold is assembled the supporting plate 2 serves as a pilot about which the mold sections are locked.

The green sand core assembly is preferably formed by positioning a split core box 6 having a cavity of any desired configuration, in a ring 7 as shown in Fig. 3 to hold the sections together. A ring 8 may be centered on ring 7 by means of dowel pins (not shown) in the parting plane of the parts constituting the core box 6. The ring 8 has a converging inner surface 9 into engagement with which the core supporting plate 2 may be brought whereby the resulting core can be accurately positioned in the plane. Green sand is poured into the cavity of the core box 6 and is compacted therein, for example, by ramming, until it fills out the cavity of the core box; then the excess sand is scraped from the core box as, for example, by passing a straight edge member across and in contact with the top of the core box. Then the ring 8 is positioned on ring 7 and box 6 and the supporting plate 2 which may be made of iron or other suitable material, is assembled in ring 8 with the projections 3 projecting into the sand and forming interlocking engagement therewith.

The green sand core assembly together with the core box 6, and plate 7, is now rolled over or inverted into the position illustrated in Fig. 4 after which the ring 7 is removed from the core box and the core box sections are parted and withdrawn from the core by sliding them apart on ring 8, ring 8 is then removed leaving the assembly shown in Fig. 5, in which the core 1 is supported upon the

plate 2. Then after the ring 8 is removed, the assembly is ready to be used in a mold.

Referring particularly to Figs. 1 and 2, in its preferred embodiment, the mold comprises a base 10 carrying a post 11 to which is hinged one end of each of the mold sections 12 and 13. The opposed ends of the mold sections are latched together by means of a clamping block 14, which is pivoted to mold section 13 and can be swung into position to cause the cam lever 15 pivoted thereto to be engaged behind the opposing mold section. Actuation of the cam lever 15 draws the two mold sections together and clamps them in position. The base 10 is provided with an opening 16 extending therethrough and of a size and shape to receive the positioning and supporting flanges 4 and 5 of the supporting plate 2 and prevent lateral movement of the plate the supporting member 2 serves as a pilot about which the mold sections are locked. This provision provides a positive means of fixing the core in position relative to the mold sections. Circumferential movement of the core supporting plate 2 is prevented by means of a lug 17 which engages in a slot in the flange 4 as can be seen in Fig. 2. The mold sections 12 and 13 are each provided with a recess, which recesses are adapted to cooperate to form a casting cavity around the core 1. Above the casting cavity and opening thereto into the mold sections 12 and 13 are provided with opposed recesses 18 which open through the top of the mold and which cooperate to form a feeder cavity through which the molten metal can be poured into the casting cavity of the mold.

In the illustrated embodiment, an auxiliary core 20 is supported upon the base 10 and protrudes through cooperating recesses in the mold sections 12 and 13 and terminates in spaced relation to the sand core 1 and in spaced relation to the inner walls of the mold sections to form an outwardly protruding casting cavity adapted to cooperate with the first mentioned casting cavity for a purpose, as, for example, to form a handle upon the article being cast.

In utilizing the device the sand core assembly is positioned upon the base 10 of the mold with the flange 4 resting thereon and the downwardly extending flange 5 is positioned in lateral engagement with the walls of the recess 16. The projection 17 fits into place in the slot of plate 2. The mold sections 12 and 13 are now swung into co-operating engagement and are locked in closed position and core 20 is inserted. The molten metal to be cast is poured through the gate 18 of the mold and permitted to flow into and around the casting cavity. Upon solidification of the metal the mold is opened and the cast article with the green sand core re-

tained therein can be removed from the mold and supporting plate 2. The core 1 can be broken away from the interior of the cast article.

By the procedure described it will be seen that a sand core has been provided which can be utilized without a supporting mandrel and without a print under situations in which a print has heretofore been necessary and that the core may be fashioned out of green sand and handled without being broken or baked.

While a specific embodiment of the invention has been shown and described it will be apparent that modifications can be made therein within the spirit and scope of the invention and such modifications are intended to be covered by the appended claims.

What I claim is—

1. A method for casting a recessed article which comprises compacting green sand into a core box, striking off the sand to form a flat surface, positioning a flat supporting member on said flat surface, inverting the supporting member and core box, removing the core box and positioning said supporting member and green sand core in a mold.

2. A method for casting a recessed article which comprises compacting green sand into a core box, striking off the sand to form a flat surface, bringing a flat supporting member into engagement with said flat surface, inverting the supporting member and core box, removing the core box, and clamping the sections of a mold about said supporting member.

3. A method for casting a recessed article which comprises compacting green sand into a core box, striking off the sand to form a flat surface, positioning a flat supporting member on said flat surface, inverting the supporting member and core box, removing the core box, positioning said supporting member and green sand core in a base plate and then locking the sections of a mold about said supporting member.

4. A semi-permanent mold for sauce pans and the like comprising a base, a pair of metallic mold halves pivoted to each other and to said base and being formed with co-operating recesses defining the side and top walls of the casting cavity, a removable metallic pilot positioned in said base and having a neck extending above the upper surface of the base and terminating in a relatively flat surface, the lower portions of said mold halves being recessed to fit about and clamp against said neck, and a green sand core for defining the internal surfaces of the article cast having a substantially flat bottom surface resting upon and spaced inwardly from the edges of the flat upper surface of said pilot and having an upper portion of greater diameter than its bottom surface, said core being

wholly out of contact with said mold halves and being engaged and supported solely by the upper surface of said pilot, the lower edge of the casting cavity being closed by a portion of the flat upper surface of said pilot.

In testimony whereof I hereunto affix my signature this 12th day of Aug., 1929.

ALLEN B. NORTON.
